Attorney.

UNITED STATES PATENT OFFICE.

CLARENCE C. LOTT, OF NEW YORK, N. Y.

VALVE-GRINDING DEVICE.

1,400,365.

Specification of Letters Patent. Patented Dec. 13, 1921.

Application filed December 28, 1920. Serial No. 433,710.

To all whom it may concern:

Be it known that I, CLARENCE C. LOTT, a citizen of the United States, residing at New York, in the county and State of New York, 5 have invented certain new and useful Improvements in Valve-Grinding Devices, of which the following is a full, clear, and exact specification.

This invention relates to devices for 10 grinding puppet valves in their seats, and is especially designed for use on internal combustion engines.

It is the object of the invention to provide a simple and inexpensive device which may 15 be easily attached to the cylinder block of an engine and adjusted from a single supporting point so as to operate on a plurality of valves located at different distances from said point. Another object is to provide 20 improved means for engaging and disengaging the valve oscillating member of the device with the valves while the supporting bracket therefor is held rigidly in place. Other objects will appear as the description 25 proceeds.

The invention will be first hereinafter described in connection with the accompanying drawings which constitute part of this specification, and then more specifically 30 defined in the claims at the end of the description.

In the accompanying drawings, wherein 35 similar reference characters are used to designate corresponding parts throughout the several views:—

Figure 1 is a broken plan view of an internal combustion engine showing one of my valve grinding devices adjusted thereto to 40 actuate one of the valves in solid lines and the position of said device when acting on another valve farther away from the point of support in dotted lines.

Fig. 2 is a vertical sectional view through 45 a portion of the top of the engine in the plane of one of the valves and the supporting bolt for the device, showing said device in operative engagement with the valve in solid lines and disengaged with said valve in dotted lines, and

Fig. 3 is a plan view of a fragment of the engine showing the valve grinding device on a larger scale than in Fig. 1.

The engine is indicated at 1 in the drawings, cylinder bores at 2 and valves at 3,

each of the latter having the usual wrench 55 receiving sockets 4 in its top.

The valve grinding device comprises a bracket 5, having a horizontal portion 6 provided with a longitudinal slot 7, and an upwardly extending arm 8 preferably arranged at an incline and having a vertical bearing 9 at its upper end for the oscillating shaft 10. Said shaft extends below the bearing and carries on its lower end a tip 11 preferably connected to the shaft by a cross 60 pin 12 and having projecting lugs 13 to engage the sockets 4 in the top of the valve 3. A coiled spring 14 is mounted around the shaft 10 so as to bear at its lower end against the tip 11 and at its upper end 70 against a washer 15 under the bearing 9. Said spring tends to press the tip 11 downward so that the lugs 13 will engage the notches or sockets 4 as shown in solid lines in Fig. 2.

The shaft 10 also extends above the bearing 9 and is bent to form the horizontally extending handle 16. To limit the downward movement of the shaft under the tension of the spring 14, a cross pin 17 is passed 80 through the upper end portion of said shaft so as to rest upon the upper end of the bearing 9. One end 18 of said pin projects from the shaft farther than the other end and is adapted to ride upon a cam surface 85 19 of arcuate form rising from one side of the top of the bearing 9 when the shaft is turned far enough around. When the shaft is turned about as shown in dotted lines in Fig. 2, and the longer end 18 of the pin 17 90 rides upon the cam surface 19, the shaft is raised against the tension of the spring far enough to disengage the lugs 13 from the sockets 4 of the valve. The shaft may be arranged and held in that position while 95 the device is being adjusted into proper position to operate upon a valve, or after one valve has been ground and the device is to be moved or swung about into position to grind another one.

The bracket is held in place during the oscillation of the shaft and valve, for accomplishing the grinding or re-seating operation, by means of a bolt 20 which may be screwed into a tapped socket 21 in the cylinder block of the engine. Said socket 21 may be one of the sockets provided for fastening the top plate of the engine to the cylinder

block or it may be formed especially for the purpose of holding the bolt, the head 22 of which is adapted to support the horizontal portion 6 of the bracket 5. A threaded shank 23 extends upward from the head 22 of the bolt and passes through the slot 7 in said horizontal portion 6 of the bracket, there being a thumb nut 24 on said shank for clamping the bracket to the bolt at any desired point along the slot so that the oscillating shaft may be positioned directly over any one of several valves without moving the bolt 20. Thus, as shown in Fig. 1, the bolt may be engaged with a socket located equidistant from two adjacent valves, and the bracket adjusted to bring the oscillating shaft directly over one of said adjacent valves, as indicated in solid lines, or said bracket, by reason of the slot 7, may be adjusted so as to bring the shaft over a valve which is farther removed from the bolt, as indicated in dotted lines.

The horizontal portion of the bracket is shown long enough in Fig. 1 to permit four valves to be reached from a single location of the supporting bolt 20, so that only one insertion of said bolt is necessary for grinding the valves for every two cylinders of an engine. The grinding is accomplished, after the shaft has been engaged with the valve, by oscillating said shaft by means of the handle 16, the pin 17 engaging the smooth upper end of the bearing 9. When it is desired to disengage the shaft from the valve, the handle is thrown farther around so as

to cause the longer end 18 of said pin to ride upon the cam surface 19, as already described.

What I claim is:

1. In a valve grinding device of the character described, the combination with a bracket having a bearing, of a shaft journaled in said bearing, resilient means for pressing one end of the shaft into engagement with a valve, and a projection on the shaft to engage the upper end of the bearing for limiting the movement of the shaft under the influence of the resilient means, said projection being adapted to move on said bearing as the shaft is rotated during the grinding operation and a fixed cam on said upper end of the bearing to be engaged by said projection during a part of its revolution for disengaging said shaft from a valve. 40

2. In a valve grinding device of the character described, the combination with a bracket having a bearing, of a shaft journaled in said bearing, resilient means for pressing one end of the shaft into engagement with a valve; a fixed cam extending 60 partially around the bearing, and a projection on the shaft to ride on said cam for disengaging the shaft from the valve against the resiliency of the pressing means, said projection also adapted to move on said bearing between the ends of the cam for oscillating the valve to grind the same. 65

In testimony whereof I have signed my name to this specification.

CLARENCE C. LOTT.
